CLAIM

The ornamental design for a medical implant device, as shown and described.

DESCRIPTION

FIG. 1 is an isometric view of a medical implant device according to a first embodiment;

FIG. 2 is a front elevation view thereof;

FIG. 3 is a rear elevation view thereof;

FIG. 4 is an elevation view thereof from the left side;

FIG. 5 is an elevation view thereof from the right side;

FIG. 6 is a top plan view thereof; and

FIG. 7 is a bottom plan view thereof.

FIG. 8 is an isometric view of a medical implant device according to a second embodiment;

FIG. 9 is a front elevation view thereof;

FIG. 10 is a rear elevation view thereof;

FIG. 11 is an elevation view thereof from the left side;

FIG. 12 is an elevation view thereof from the right side;

FIG. 13 is a top plan view thereof; and,

FIG. 14 is a bottom plan view thereof.
